York, N. Y., assignor to Radio Corporation of
America, a corporation of Delaware

Application September 9, 1942, Serial No. 457,711

8 Claims. (Cl. 250—17)

This invention relates to a new and useful voltage supply circuit, and is particularly adapted to obtaining screen voltage for a class "C" radio frequency amplifier tube and also the anode voltage for its driver tube.

An object of this invention is to provide an improved arrangement for supplying screen and anode voltages to a radio transmitter, particularly one which is modulated by keying.

A feature of this invention is the elimination for the need of a fixed bias supply for the driver tube, and also to reduce the amount of fixed bias voltage necessary to obtain anode current cut-off in the amplifier tube, particularly when the excitation connected to the driver tube is modulated by being keyed for break in operation.

The ordinary series screen resistor as used in the prior art is not practicable for a screen grid tube used as a class "C" radio frequency amplifier, the excitation of which is modulated by being keyed, for the reason that when the space current in the tube is reduced to a low value under key-up conditions by the normally cut-off fixed bias, the screen voltage will rise considerably. This, in turn, necessitates a very high value of fixed bias to keep the anode current and dissipation within reasonable limits.

By this invention, the driver tube can obtain its anode voltage from the same series resistor that supplies the screen of the final tube, and thus reduces the fixed bias necessary to obtain the proper anode current cut-off in the amplifier.

The invention will best be understood by referring to the accompanying drawing, in which a circuit diagram of the invention is shown.

The keyed oscillation stage 1, which may be any suitable form of oscillation generator for developing the desired oscillations, is connected to an electron discharge device 2, which is preferably of the pentode type, such as the RCA #47. Device 2 is provided with a grid 3, anode 4, screen grid 5, suppressor grid 6 and cathode 7. The device 2 serves as the driver stage of a second electron discharge device 8, which acts as a radio frequency amplifier stage and is preferably of the RCA #813 type of transmitting beam power amplifier.

The electron discharge device 8 includes input grid 9, screen grid 10, anode 11, beam-forming electrodes 12 and 13, and cathode 14. Resistance 16, connected between ground and grid 3, forms a direct current return path for grid 3.

The key circuit includes a key 15, which is coupled to grid 3 by a condenser 17. A coupling condenser 18 is connected in series between anode

5 4 and the input grid 9 of the radio frequency stage. A tuned circuit, including inductance 19 and variable condenser 20, is connected from anode 4 to the source of high voltage 21. A grid bias resistor 22 is connected from grid 9 to a source of grid bias voltage indicated as —C. A second tuned circuit, including inductance 23 and variable condenser 24, is connected to anode 11 of the radio frequency stage, and to the high voltage source 21. A series resistor 25 is provided for supplying the proper voltage on screen 10 and is so adjusted that the normal operating anode and screen voltages appear on the buffer 2 and the final tube 8 under key-down conditions.

In the operation of the circuit of this invention when the key 15 is up, or open, the anode resistance of the electron discharge device 2 drops to a low value, since its bias voltage is zero. 20 Because of resistance 25 the anode voltage of tube 2 and the screen voltage of tube 8 drops to a low value. This circuit arrangement saves an additional power supply for the anode of tube 2, the screen 10 of tube 8, the bias supply for grid 3 of tube 2, and enables a relatively low value of fixed —C bias to be used for tube 8.

If desired, additional resistors 26 and 27 can be inserted in series with resistor 25 to properly 30 adjust the voltages on screens 6 and 10. A bypass condenser 28 is connected between screen 6 and ground. Likewise, a bypass condenser 29 is connected between screen 10 and ground 30.

The beam-forming electrodes 12 and 13 connect to ground 30 and are provided with condensers 31 and 32. In brief, it is to be noted 35 that tube 2 is provided with a resistor 16 connected between the grid 3 and cathode 7. Consequently, in the absence of oscillations from source 1, tube 2 draws current, and in the presence of in-put from source 1, the plate grid of tube 2 is reduced. On the other hand, the plate current flow through tube 8 is just the reverse for the reason that this tube is substantially 40 cut-off by the —C voltage impressed through resistor 22 on the grid 9. When keyed oscillations reach the grid 9 of tube 8, plate current flow through tube 8 increases. Hence, it should be apparent that during periods of "no signal" 45 the current flow through tube 2 produces a voltage drop in resistor 25, which serves to cut down the screen voltage on screen grid 10.

This invention should not be limited to the precise circuit application shown, as it is to be distinctly understood that it is capable of being

used in other circuit applications where similar circuit characteristics exist.

What is claimed is:

1. In combination, a source of modulated high frequency voltage, a first tube having an anode, a cathode, a grid and a screen grid, a second tube having an anode, a cathode, a grid and a screen grid, a coupling between said modulated high frequency voltage and the grid cathode circuit of said first tube, circuits coupling the anode and cathode of the first tube to the grid and cathode of the second tube, a resistance connected across the grid and cathode of the first tube serving to permit flow of current through said first tube in the absence of excitation from said source of said modulated high frequency voltage, a source of potential for maintaining the grid of the second tube negative with respect to the cathode of the second tube, a source of anode potential for said tubes, and a resistor connected to said source of anode potential and to the screen grids of both of said tubes.

2. In combination, a source of keyed high frequency voltage, a first tube having an anode, a cathode, a grid and a screen grid, a second tube having an anode, a cathode, a grid and a screen grid, a coupling between said source of high frequency voltage and the grid cathode circuit of said first tube, circuits coupling the anode and cathode of the first tube to the grid and cathode of the second tube, a resistance connected across the grid and cathode of the first tube serving to permit flow of current through said first tube in the absence of excitation from said source of keyed high frequency voltage, a source of potential for maintaining the grid of the second tube negative with respect to the cathode of the second tube, a source of anode potential for said tubes, and a resistor connected to said source of anode potential and to the screen grids of both of said tubes.

3. In combination, a source of keyed high frequency voltage, a first tube having an anode, a cathode, a grid and a screen grid, a second tube having an anode, a cathode, a grid and a screen grid, a coupling between said source of keyed high frequency voltage and the grid cathode circuit of said first tube, parallel tuned circuits coupling the anode and cathode of the first tube to the grid and cathode of the second tube, a resistance connected across the grid and cathode of the first tube serving to permit flow of current through said first tube in the absence of excitation from said source of keyed high frequency voltage, a source of potential for maintaining the grid of the second tube negative with respect to the cathode of the second tube, a source of anode potential for said tubes, and a resistor connected to said source of anode potential and to the screen grids of both of said tubes.

4. In combination, a first tube having an anode, a cathode, a grid and a screen grid, a second tube having an anode, a cathode, a grid and a screen grid, circuits coupling the anode and cathode of the first tube to the grid and cathode of the second tube, a resistance connected across the grid and cathode of the first tube serving to permit flow of current through said first tube in the absence of excitation, a source of potential for maintaining the grid of the second tube negative with respect to the cathode of the second tube, a source of anode potential for said tubes, a resistor connected to said source of anode potential and to the screen

grids of both of said tubes, and an input circuit coupled to the grid and cathode of said first tube for applying modulated high frequency voltages thereto.

5. In combination, a source of keyed high frequency oscillation voltage with a coupling circuit connected thereto, a pair of cascade electron discharge devices, each having anode, grid, cathode and screen grid electrodes forming a keyed oscillation circuit, and a radio frequency amplifier circuit respectively, said coupling circuit connected to the grid cathode circuit of the electron discharge device which forms the keyed oscillation circuit, a source of voltage for supplying voltage to said electron discharge devices, a series resistor connected to said source of voltage and to the anode cathode circuit of at least one of said electron discharge devices and forming a part of a voltage divider, and the other electron discharge device forming the other part of said voltage divider.

6. A radio transmitting circuit, a source of high frequency voltage, a keyed oscillation circuit coupled to said source of high frequency voltage including an electron discharge device having anode, grid, cathode and screen grid electrodes, a grid-leak bias arrangement for connection to the input grid of said electron discharge device, a radio frequency amplifier circuit including an electron discharge device having a screen grid and input electrodes coupled to the anode of said first electron discharge device, and having output electrodes, a source of voltage supply connected to said output electrodes of said second device, a resistor connecting the anode to cathode impedance of said first electron discharge device in series with said source of voltage supply, said anode to cathode impedance and said resistor forming a voltage divider connected with said source of high frequency voltage, and connections from said voltage divider to the screen grid of said first and second electron discharge devices.

7. In a radio telegraph transmitter a source of high frequency voltage, a keying circuit for said transmitter coupled to said source of high frequency voltage, said circuit including an electron discharge device having anode, grid, cathode and screen grid electrodes, a grid leak connected to the input grid of said electron discharge device, a radio frequency amplifier circuit including an electron discharge device having anode, grid, cathode and screen grid electrodes, a source of voltage supply, a resistor connected in series with said source of voltage supply and the anode of at least one of said electron discharge devices, the screen grid electrodes of both of the electron discharge devices being connected with the source of voltage supply so that the first mentioned electron discharge device obtains its anode voltage from said resistor, which supplies the screen grid voltage to said radio frequency amplifier circuit electron discharge device.

8. In a radio telegraph transmitter a source of high frequency voltage, a keying circuit for said transmitter coupled to said source of high frequency voltage, said circuit including an electron discharge device having anode, grid, cathode and screen grid electrodes, a grid leak connected to said electron discharge device, a radio frequency amplifier circuit including an electron discharge device having anode, grid, cathode and screen grid electrodes, a source of voltage supply, a resistor connected in series with said source of voltage supply and the anode of at least one of

said electron discharge devices, a variable resistor connected in series between said screen grid of said second electron discharge device and said first mentioned resistor, the screen grid electrode of the first mentioned electron discharge device being connected with the source of voltage supply and said first mentioned resistor so that it obtains anode voltage from said first mentioned

resistor and the first mentioned electron discharge device which serves as part of the voltage divider for said second mentioned electron discharge device.
